HAROLD B. SMITH, OF WORCESTER, MASSACHUSETTS, ASSIGNOR TO WESTINGHOUSE ELECTRIC & MANUFACTURING COMPANY, A CORPORATION OF PENNSYLVANIA

INSULATOR

Application filed July 13, 1923. Serial No. 651,246.

My invention relates to insulators and particularly to high-potential insulators of the suspension type.

One object of my invention is to provide an insulator of the above-indicated character that shall permit the proper spacing of high-potential transmission conductors and, at the same time, employ laterally extending annular field-controlling members of relatively great diameter.

Another object of my invention is to provide means for so grouping and mounting a plurality of high-potential suspension insulators as to prevent the detrimental effects sometimes caused by violent winds.

Another object of my invention is to provide a high-potential insulator in which the danger of arc-over during wet conditions is effectually reduced.

A further object of my invention is to provide a high-potential insulator that shall be simple and durable in construction and economical to manufacture.

Heretofore, in the art of supporting high-potential transmission conductors, it has been the most general practice, in commercial service, to attach the conductors to the upper ends of rigid insulators projecting upwardly from cross-arms of poles or towers and to attach the conductors to the lower ends of insulators hung flexibly from the lower sides of the cross arms.

Attempts have been made, in high-voltage service, to utilize rigidly depending insulators but no high-voltage insulators of this type have been extensively adopted because of the relation of the length and weight of the insulators to the voltages of the conductors supported thereby. In insulators, as heretofore employed, the length and weight thereof have been such that, for voltages up to a certain general value, the rigid or pin type have been most advantageously mounted above the cross arms.

For voltages above the values for which the rigid pin-type insulator is employed, the flexibly suspended insulator has been employed because of the increased length and weight thereof. However, the swaying of the flexibly suspended insulators and the conductors

makes it necessary that the conductors be placed relatively far apart, resulting in larger and more expensive cross-arms and towers.

My invention does not contemplate the mere inversion of an ordinary insulator of the rigid pin type so that the conductor hangs below the cross arm because, for the same voltages that could heretofore be resisted by such an insulator, the mechanical conditions would be but little varied, there would be practically nothing gained and no invention would be involved.

In my prior Patents #1,730,250 of Oct. 1, 1929 and #1,729,691 of Oct. 1, 1929, are set forth structures by which the length of an insulator may be very materially reduced for a given voltage.

The first above-mentioned patent discloses an insulator in which the terminal members are so constructed as to form what may be termed a "hollow" field, through the weakest portion of which the insulator extends, and in which the insulator is also so formed as to take full advantage of the weakened center of the field. In other words, the terminal members and the insulator are so constructed and combined as to free the insulating member entirely of corona-forming stresses.

The second of the above-mentioned patents sets forth an insulator that materially increases the value of the first, under wet conditions, by removing the water-drip portion from the zone of maximum potential gradient, as will be apparent by referring to the application. As a result of the above-mentioned developments in the insulator art, a rigid insulator is obtained which is the equivalent in ability to withstand high voltages of a former insulator, which, by reason of its length, would not be mechanically adapted for rigid mounting at one end only, either vertically above or below a cross arm.

In the insulators of all of the prior patents herein mentioned, I employ an upper field distributing and directing member of relatively great diameter. Thus, when adapting the member to an insulator of the rigid pin type above a cross arm, it will be of the same potential as the conductor which it sup-

ports. Consequently, in designing the tower or support, the spacing of the field distributing member, as well as the spacing of the conductors, must be taken into consideration. In other words, the outer edges of the relatively widely extending field distributing members must in that form be spaced as far from each other as would be the conductors ordinarily.

In providing a flexibly suspended insulator with such an upper field controlling member, the lateral extent of the member must also be taken into consideration in providing proper spacing and lateral swing of the conductor.

Hence, with either the rigid pin-type insulator above the cross-arm or the flexible suspension insulator below the cross-arm, certain space and structure considerations are necessary.

In practicing my invention, I provide a rigid insulator, rigidly suspended from the underside of a support or cross arm, that comprises a laterally extending upper-field-controlling member which is grounded to the cross-arm, and is provided with an annular intermediate portion of maximum potential gradient adjacent to its surface. A lower terminal member, of substantially toroidal shape having a rim portion of relatively great radius, surrounds the longitudinal axis of the insulator in spaced relation thereto and cooperates with the upper field-controlling member.

Since the upper field-controlling member is grounded, it may be placed as close to other similar members as desired to ensure the proper spacing of the conductors. Thus, since the wide spacing of the upper field controlling members, as in the pin-type insulator above the cross-arm, is eliminated and the members do not sway with the wind, as in the flexibly suspended type of insulator, an effective and economical structure is obtained.

Flexibility for the conductor and compensation for lateral stresses in the insulator are obtained by a flexible extension at the lower end of the insulator.

Figure 1 of the accompanying drawings is an elevational view of a portion of a high-tension transmission structure, as viewed in the direction of the conductors, with a plurality of insulators constructed and grouped in accordance with my invention, and

Fig. 2 is an enlarged view, partially in elevation and partially in section, of one of the insulators shown in Fig. 1.

In general, the device embodying my invention may comprise a support or pole 1, only the upper portion of which is shown, cross-arms 2 thereon and a plurality of insulators 3.

The latter are preferably constructed as shown in Fig. 2, each comprising an elongated preferably plain cylindrical insulating member 4 having end portions 5 and 6

that are screw-threaded, or otherwise suitably formed, to receive socket terminal members 7 and 8, respectively. The upper socket member 7 is provided with a flange 9, or is otherwise suitably formed for rigid attachment to the cross-arm 2, as by bolts 10.

A preferably sheet-metal member 11 of substantially hood shape is secured to the upper socket member 7 and comprises an outer perimetral water-drip portion 12 and an intermediate annular portion 14 of maximum potential gradient, adjacent to its surface as will hereinafter more particularly be pointed out.

The lower socket member 8 supports a preferably short cable member 15 or any suitable device, such as a pivoted link, to receive and support a conductor 16. This construction compensates for lateral wind pressure and permits the conductor 16 to swing laterally without transmitting movement to the insulator. A portion 17, which may be a separate member or integrally formed on the socket member 8, is of substantially ring or toroidal shape, surrounding the insulating member 4 in spaced relation thereto, and secured to the socket member 8, as by a flange 18. Openings 19 are provided in the flange 18 for the escape of moisture.

The shortest distance from metal to metal, between the members 7 and 8 along the surface of the insulating member 4, is greater than the distance shown by a dotted line X, between the member 17 and the portion 14 on the member 11. At the upper end of the line X, the portion 14 is curved about a relatively wide radius to prevent undue concentration of the electric field thereon and provides an annular zone of maximum potential gradient adjacent thereto. The member 17, at the lower end of the line X is similarly of relatively wide radius.

The above described construction causes the electric field to be of maximum intensity along the line X, but, since the surfaces of the portions 17 and 14 are widely curved, substantially the maximum break-down strength of the air is obtained.

The curvature of the portions 17 and 14 also causes the electric field strength to become weaker substantially in proportion to the distance removed from the line X in either side of the latter. Thus, the insulating member 4 extends through a portion of the field that is so weakened, and directed along lines substantially parallel to its sides, that corona never tends to form thereon. Also, the water drip portion 12 on the member 11 is so removed from the line X as to effectually prevent any considerable reduction in the break-down voltage of the insulator under wet conditions.

Being grounded to the cross-arms 2, the members 11 on one cross arm may be placed as close to each other as desired, it being only

necessary to properly space the lower and smaller live ends of the insulator. This construction provides advantages, as pointed out above, over an ordinary rigidly depending insulator and is an improvement over the insulators of my herein mentioned prior patents whether they be mounted rigidly above, or flexibly suspended from, the cross arms.

10 While I have shown and described a particular form of my invention, changes may be effected therein without departing from the spirit and scope thereof, as set forth in the appended claims.

15 I claim as my invention:

1. In a high-potential insulator device, the combination with a main supporting structure, of a plurality of insulators depending therefrom each comprising a grounded laterally-projecting upper electrostatic-field-controlling terminal member having a widely-rounded toroidal portion intermediate its outer extremity and the longitudinal axis of the insulator advanced from the adjacent portions thereof toward the lower end of the insulator, an elongated insulating member depending from said member, a positive lower terminal member of lesser lateral extent and co-operating with the upper terminal member to confine flashover thereto to said advanced portion and to direct a weakened central field portion substantially parallel to said insulating member, and means for connecting all of said parts in fixed relative positions.

2. In a high-potential insulator device, the combination with a main supporting structure, of a plurality of insulators depending therefrom each comprising a grounded annular laterally-projecting upper electrostatic-field-controlling member of relatively great diameter, an elongated insulating member depending therefrom, a positive laterally-projecting lower electrostatic-field-controlling member of lesser diameter, disposed outside, and co-operating with, said upper member to confine flash-over thereto to a position laterally between the outer perimeter thereof and the insulating member and to direct a weakened central field portion substantially parallel to said insulating member, and means for connecting all of said parts in fixed relative positions.

3. In a high-potential suspension insulator, the combination with a supporting structure, of a plurality of elongated insulating members depending therefrom, each having rigidly-connected grounded upper, and positive lower, terminal members adapted to direct a weakened central field portion substantially parallel to said insulating member and each upper terminal member comprising an annular laterally-projecting electrostatic-field-controlling portion of relatively great diameter, said laterally-projecting portion

having an annular toroidal portion intermediate its axis and perimeter advanced from the adjacent parts thereof toward the lower terminal member, and means for rigidly securing each insulator to said supporting structure to permit the upper field-controlling members of the respective insulators to be placed relatively close to each other.

In testimony whereof, I have hereunto subscribed my name this tenth day of July, 1923.

HAROLD B. SMITH.
